UNITED STATES PATENT OFFICE

109,203

DESIGN FOR A COMBINED DESK AND CHAIR

Willard H. Bond, Jr., East Grand Rapids, Mich., and Onnie Mankki, Cleveland Heights, Ohio,
assignors to American Seating Company, Grand Rapids, Mich., a corporation of New Jersey

Application February 14, 1938, Serial No. 75,124

Term of patent 14 years

To all whom it may concern:

Be it known that we, Willard H. Bond, Jr. and Onnie Mankki, citizens of the United States and residing, respectively, at East Grand Rapids, in the county of Kent and State of Michigan, and at Cleveland Heights, in the county of Cuyahoga
and State of Ohio, have invented a new, original, and ornamental Design for a Combined Desk and Chair, of which the following is a specification,

reference being had to the accompanying drawing,
forming a part thereof, in which:

The figure is a perspective view of the article
showing our new design.

We claim:

The ornamental design for a combined desk
and chair, substantially as shown.

WILLARD H. BOND, JR.
ONNIE MANKKI.
